WEATHER STRIP

Irwin C. Elmer, Atlanta, Ga.

Application September 19, 1938, Serial No. 230,664

4 Claims. (Cl. 20—69)

The invention relates to weather strips and has as an object the provision of a simple form of strip which may be easily applied and is efficient in action.

5 It is a further object of the invention to provide a weather strip which will have line contact with two of the surfaces of a closure, as a window or a door.

Further objects of the invention will appear 10 from the following description when read in connection with the accompanying drawing showing illustrative embodiments of the invention, and wherein:

15 Figure 1 is a horizontal section through a window opening and sash therein showing the weather strip of the invention in place;

Fig. 2 is a perspective view of the strip of Figure 1; and

20 Fig. 3 is a horizontal section showing the strip applied to a doorway.

The weather strip of the invention is desirably formed of an integral strip of material folded to form. As shown it comprises a base plate member 10 having openings 11 to receive fastening elements 12 whereby the strip is secured to the jamb of an opening.

25 The integral strip is shown in Figure 2 as folded at 13 to provide a plate member 14 extending at an acute angle to the base plate member 10, the resilience of the metal tending to hold the member 14 and its carried parts in about the normal position shown in Figure 2 and to be somewhat compressed toward the base plate member in use.

30 The strip of material of which the article is formed is again folded at 15 to provide the plate member 16, the last named fold also being at an acute angle, and the plate members 10, 14, and 16 being of substantially Z-form.

35 A third fold of the metal at 17 provides a plate member 18 desirably terminating in a curved margin 19 for contact with the face 20 of a closure. The plate member 18 desirably extends at a little less than a 90° angle to the member 16.

40 The fold 15 when the device is to be used upon a window is desirably deflected away from the plate 10 to provide an edge having contact with the closure, at the same time keeping the plate member 16 clear of such contact. The result of this structure is a clear line contact with the edge

45 of the closure, thus applying the pressure resulting from the resilience of the fold 13 all at the one line, which results in a greater pressure per square inch than would be the case if the entire

surface of a considerable portion of the surface of plate 16 contacted the closure.

For the same reason the curve 19 is provided upon the margin of the plate member 18. The plate member 16 is shown as normally outwardly 5 deflected from its jamb contacting margin whereby, due to its resilience, stress will be applied to the member 14 at fold line 13 and said member 14 and the sash contacting and embracing members 16 and 18 will be urged, as a whole, toward 10 the sash. The structure made up of members 16 and 18 will therefore be floatingly supported in a manner to coat with the sash even though there is a substantial space between the sash and its runway as often occurs in a poorly fitted sash 15 or in very old structures.

As shown in Figure 1, the jamb of a window is indicated at 21, the inside trim at 22, the window stop at 23, parting strip at 24, the lower sash at 25, the upper sash at 26, the check rails at 21, 20 the blind stop at 28, and the outside window casing at 29. Where the sash of the window to which the strip of the invention is to be applied is loose enough to not require dressing, the strips may be installed without removing the sash. 25 This may be accomplished by sliding the upper sash clear down, inserting the lower end of the strips downwardly into place for the necessary lap, nailing the major portion of the margins of plate 10, then returning the sash to raised position and placing a nail 12 in the then exposed lower end of the strip. The lower sash may be manipulated in the same manner—reversed.

30 In the form as shown applied to a door in Figure 3, the margin 15 is shown as curved in such 35 a direction as to cam against the corner 30 of the door when the door is closed. The action of the invention as applied to a door with this exception is the same as that already described.

An important feature of the invention is the 40 floating support of the closure contacting plate members 16 and 18. The fold lines 13 and 15 provide a flexibility of support for the plates 16 and 18 which with the resilient connection between those two plates at 17 and the floating 45 support of the portions 14, 16 and 18 upon the movable fold line 13, enable the strip to accommodate itself widely to shrinkage or swelling of a door or sash by angular movement of the angle member 16, 18 about the fold line 15 or 13 or 50 both.

Minor changes may be made in the physical embodiments of the invention without departing from the spirit thereof within the scope of the appended claims.

I claim:

1. A weather strip formed of an integral strip of resilient material folded to provide: a base plate member to be secured to a face of an opening; a plate member forming an acute angle with said base member; a second plate member forming an acute angle with the second named plate member, the fold between the second and third named plate members to press against the edge of a closure opposing a jamb of said opening and a fourth plate member projecting at a less acute angle from the edge of the third named plate member, the free edge of the last named plate member to press against a face of the closure.
2. The structure of claim 1 with the portion of the base plate member adjacent the fold thereof deflected from the plane of the free margin of said member, whereby to floatingly support the remainder of the structure.

3. A weather strip comprising, in combination: a strip of resilient metal folded to present a base plate member to be secured at its edge to a jamb of an opening; said strip twice folded upon said base plate to provide two strip members in Z relation with said base plate member whereby the three strip members thus provided including the base plate member may stand between said jamb and an edge of the closure; said metal strip formed with a third fold at an angle less than 90° to provide with the third strip member an angular corner-of-the-closure-embracing means to contact the closure at lines upon the edge and a face of the closure.

4. The combination of claim 3 with said base plate deformed to cause the folded edge thereof to stand away from the jamb whereby to provide floating support for the closure contacting portions of the device.
